COIL WINDING MACHINE

Edward W. Collins, Anderson, Ind., assignor, by
mesne assignments, to General Motors Corpora-
tion, Detroit, Mich., a corporation of Dela-
ware

Application February 11, 1933, Serial No. 656,244

84 Claims. (Cl. 140—92.2)

This invention relates to coil winding machines and more particularly to a machine for winding coils such as disclosed in the patent of Jasper F. Cullin, No. 1,926,331 issued September 12, 1933.

This application is a continuation in part of my copending application Serial No. 568,496, filed October 12, 1931.

An object of the present invention is to provide a machine which operates rapidly and efficiently to wind coils such as those above mentioned.

Still further objects will readily occur to those skilled in the art upon reference to the following description and the accompanying drawings in which:—

Figs. 1 and 1a together form a top plan view of the machine.

Figs. 2 and 2a together form an elevation view of the machine.

Fig. 3 is an end view of the machine.

Fig. 4 shows the coil which is wound on the machine.

Fig. 4a is a sectional view taken on the line 4a—4a of Fig. 4.

Fig. 5 is a section on line 5—5 of Fig. 4.

Fig. 5a is a view of the coil looking in the direction of arrow 5a in Fig. 4.

Fig. 6 shows the clutch operating mechanism and is a section on line 6—6 of Fig. 1.

Fig. 7 is a section on line 7—7 of Fig. 6.

Fig. 8 shows a stopping mechanism for the machine, and is a section taken on line 8—8 of Fig. 1a.

Fig. 9 is a view similar to Fig. 8 showing, however, the stopping mechanism in another position.

Fig. 10 is another view of the stopping mechanism looking in the direction of arrow 10 in Fig. 9.

Fig. 11 shows the winding head and is a section on line 11—11 of Fig. 1a.

Fig. 12 is a plan view of the winding head and the form, and is a view looking in the direction of arrow 12, Fig. 2a.

Fig. 13 shows part of the cutting blades, and is a view looking in the direction of arrow 13, Fig. 12.

Fig. 14 is a partial plan view of the cutting blades and is taken along arrow 14, Fig. 13.

Fig. 15 is an edge view of the blades, and is taken along arrow 15, Fig. 13.

Fig. 16 discloses the wire shifting mechanism and its actuator as viewed in the direction of arrow 16, Fig. 1a.

Fig. 17 shows the wire shifting mechanism, and is viewed in the direction of arrow 17 in Fig. 16.

Fig. 18 shows the actuating mechanism for the cutting blades and is taken on the line 18—18 of Fig. 2a.

Figs. 19 and 20 are perspective views of the cutting blades.

Figs. 21 and 22 are fragmentary perspective views of the machine.

Figs. 23 to 45 inclusive, together illustrate in a diagrammatic manner the development of a coil on the winding form.

Fig. 46 is a diagrammatic view of the winding form, one side wall of the same being omitted for better illustration of the bottom of the winding groove.

Fig. 47 is a top view of a coil end receiving groove portion of the winding form and is viewed in the direction of arrow 47.

Figs. 48 to 55 inclusive, are fragmentary sectional views taken on the lines 48—48, 49—49, 50—50, 51—51, 52—52, 53—53, 54—54 and 55—55 of Fig. 47.

Referring to the drawings and particularly to Figs. 4 to 5a inclusive, there is shown the coil which is disclosed in the Cullin application referred to. In these figures there is disclosed a two-wire coil having a plurality of (seven) turns. One wire is striped and the other plain to distinguish them. The striped wire is designated by reference numeral 148 and its cross section is solid black. The plain wire is designated by numeral 147 and its cross-sectional view is cross-hatched. The active coil sides 130 and 131 are wrapped, while the coil end portions 132 and 133 are uncovered.

The coil is wound so that cross sections thereof through the active coil sides 130 and 131 are substantially in the form of elongated quadrilaterals and so that the long dimensions of said cross sections are substantially parallel and are inclined to the median plane of the coil.

It necessarily follows that a machine for winding a coil of this description must include a rotatable winding form of peculiar shape and a movable wire shifter which cooperates with the form in a particular manner in order to produce the coil of the Cullin application. Before describing the machine, attention is directed to the disclosures in Figs. 23 to 45 inclusive, wherein in a diagrammatic manner the development of the coil on a winding form is illustrated. As shown in Fig. 4a, the four coil sides are designated by numerals 130, 131, 132 and 133 which together form a substantial quadrilateral. In Figs. 23 to 55

45 inclusive, Figs. 23, 27, 31, 35, 39 and 43 illustrate the development of active coil side 130, Figs. 24, 28, 32, 36, 40 and 44 illustrate the development of coil end portion or coil side 132, Figs. 25, 29, 33, 37, 41, and 45 illustrate the development of active coil side 131, and Figs. 26, 30, 34, 38 and 42 illustrate the development of coil end portion or coil side 133. It appears from Figs. 4, 4a, 5a and 24 that in the opposite coil sides 130 and 131 all 10 wires run parallel, whereas in the coil sides 132 and 133 the wires cross each other. It is therefore apparent that due to the crossing of the wires in coil sides 132 and 133, the other coil sides 130 and 131 have to be developed from opposite directions. 15 This appears clearly from Figs. 27, 28, 29 and 30 in which the heavily marked wires together illustrate the winding of a single turn of the coil. The coil itself is wound from two continuous wires. It will be noted in these figures that part 130a 20 of the single turn which is part of coil 130 is located on the right-hand side of a winding form 135, that the continuation of part 130a crosses over to the left hand side of said winding form as part 132a of coil side 132, that the continuation of part 132a remains on the left-hand side of said winding form as part 131a of coil side 131 and that the continuation of part 131a crosses over to the right-hand side of said winding form as part 133a of coil side 133. In comparing the successive Figures 27, 31, 35, 39 and 43, it appears 25 that the coil side 130 is developed from the right-hand side of winding form 135 and in comparing the successive Figs. 25, 29, 33, 37, 41 and 45 it appears that coil side 131 is developed from the left hand side of said winding form. In order 30 to assure a snug engagement between the successively deposited wires of coil side 130, a surface 136 of the winding form is slightly tapered so that during winding the mere tension which is applied to the wires causes the same to yield 35 against previously deposited wires of coil side 130. Likewise a surface 137 of the winding form is slightly tapered so that the wires of coil side 131 are yielded against each other, respectively 40 against the left hand side of winding form 135 as viewed in these figures. The wires under tension which are crossing from one side of the winding form to the other side thereof naturally have a tendency to loosen the snug engagement between 45 the wires of coil sides 130 and 131, in spite of the provision of the tapered form surfaces 136 and 137 whose tapers are shown exaggerated in the diagrammatic illustration of Figs. 23 and 24. In 50 order to counteract such tendency of the crossing wires, surfaces 139 and 140 of the winding form 135 are so tapered that the wires 132a which connect wires 130a and 131a are yielded in the same direction as wires 130a and 131a for some 55 distance from the intersections of wires 132a with wires 130 and 131a as appears clearly from Figures 27, 28 and 29. Likewise surfaces 138 and 141 of the winding form are so tapered that the wires 133a which connect wires 131a and 130b are yielded in the same direction as wires 131a and 130b as appears clearly from Figures 29, 30 60 and 31. It is therefore apparent that all the mentioned tapered surfaces of the winding form co- 65 operate to produce a compact coil.

Having realized that due to the crossing wires in coil sides 132 and 133 it is necessary to develop the other coil sides 130 and 131 from opposite directions, it then follows that in order to have the start and the end leads of a coil emerging from the active coil sides 130 and 133 and in the same direction they would necessarily be located

in the same end plane of a coil. In order to locate the start leads in one end plane and the end leads in the other end plane of a coil, one of the leads is deposited in an end plane of the coil which is opposite to that from which that active coil side is developed from which said one of the leads emerges. Naturally the tapered surfaces of the winding form which assist in the proper development of all coil sides would interfere with such extraordinary deposition of one of these leads. 10 In the present instance the start leads 130c of a coil to be wound are deposited in consecutive grooves 142 and 142a in the winding form which lead to the form surface 143, whereby the tapered form surfaces 136 and 139 cannot interfere with the extraordinary deposition of start leads 130c. At the end of the natural winding course the end leads 131b are located adjacent form surface 144 as appears from Fig. 45.

The surfaces 145 and 146 of winding form 135 20 are curved so as to give the crossing coil sides 132 and 133 a desired shape. The closest distance between these surfaces which is at the median crossing points of the wires of these coil sides is twice the thickness of a wire. This appears obvious from Fig. 4a where the median crossing points of coil sides 132 and 133 are shown in section.

There will now follow a brief description of the operations performed by the machine in order to produce a coil. Form wound coils of the kind shown in Fig. 4 are wound on the revolving winding form 135 which has laterally displaced outwardly projecting portions, disposed in a plane perpendicular to the axis of rotation of 30 the form, to provide wire holding means. In winding a coil, leading ends of the wires, as they come from the feed spools, from which the coil is wound, are hooked or anchored to an end of the wire holding portion. The form is then rotated and the wires are shifted laterally in a certain order to be described later. A suitable number of turns is given the form and on the last turn, the end wires are displaced, to be returned to the wire holding portion, where they are cut 40 to free the trailing ends of the coil. Before the cutting action takes place, however, the wires must be clamped to the winding form and more particularly, between the knife and the spools so as to provide anchors for the leading ends of 45 the next coil to be wound. In the disclosed machine, the anchors are bent so as to be hooked in the wire holding portion and then are cut off from the completed coil leading ends, while anchors for the next coil are being formed and bent. 50 Accordingly, two cuts are made in each cutting action, one, to cut the completed coil trailing ends from the anchors of the next coil, and the other, to cut the anchors off the leading ends of the completed coil. These cuts are performed 55 automatically in the machine by means of parallel blades in the wire holding portion which move automatically in parallel planes transverse to the wires to be cut. The blade whose cutting edge cuts off the anchors of the leading ends of 60 the completed coil, has a bending edge which moves in the same plane, transverse to the wires, as the cutting edge. This part of the blade, namely, the bending edge, bends the wires to 65 form anchors for the next coil to be wound. The anchor cutting edge and the anchor bending edge are relatively displaced, however, in that plane, with the cutting edge below the bending edge, so as to move in different paths, with the anchors to be cut off below the wires to be bent 70 75

into anchors. Accordingly, insurance is given against the possibility of the anchor cutting edge traversing and cutting the leading ends of the wires of the next-to-be-wound-coil, which latter are, at that time, being traversed by the anchor bending blade, thereby to be bent into anchors. In effecting this insurance, there has been provided means to move down the anchors after they are formed, and before the coil is completely wound, so as to be in the path of movement of the anchor cutting edge and so as to be below and out of the path of movement of the anchor bending edge. Further, means are also provided to insure the positioning of the trailing ends of the wound coil above the anchors of the same coil. These trailing ends, being above the anchors, are in the path of movement of the anchor bending edge, but are above and out of the path of movement of the anchor cutting edge.

The winding form 135 of the machine includes two major parts, one of which is laterally shiftable to and from the other. The relatively stationary part, hereafter called the head, is disposed on the end of a rotatable shaft and has a face perpendicular to the axis of rotation of the shaft, and against which face may be clutched or pressed a face of a shiftable part, hereafter called the form. The cooperating faces have dovetailing and clutching portions for insuring their proper alignment and for relatively spacing the faces to provide a groove in which the coil may be wound. The form is disposed on the end of an axially shiftable shaft, hereafter called the tail shaft, loosely mounted, so as to permit itself and the form to be rotated with the head when the latter and the form are relatively clutched. The cooperating head and form which together constitute the winding form 135 provide the earlier explained winding groove. Projecting laterally from and forming an integral part of the head is the wire holding portion. The latter has at its end two relatively transverse grooves, in one of which are laid the wires to be cut and bent, and in the other of which the blades move to traverse the wires. The wire receiving parts are more distanced from the axes of the shafts than are the shoulders of the grooves and accordingly, the coil is formed with leads 130c and 131c projecting therefrom, these being what were referred to above as the leading and trailing ends, respectively, of the coil being wound.

Construction of the machine

Referring to Figs. 1 to 3 inclusive, and 6 to 22 inclusive, the head 200 is disposed on the end of a shaft 212, hereafter called the head shaft. The latter is provided with a clutch for connecting it to a constantly rotating belt or chain driven pulley 214, loosely rotating on the head shaft. Locking and operating means for the clutch are also provided, and these may, in part, be controlled by the operator. Paralleling the head shaft and in back of it, is a counter shaft 216 which is rotated step by step from the main shaft and which is provided with cams, etc. for controlling the travel of the wires as they are being fed to the head. The counter shaft also serves automatically to control the clutch operating and locking means. Aligned with the head shaft and with one end near the head, is a tail shaft 218, (see Figs. 1a and 2a) mounted so as to move axially toward and away from the head shaft. On the end thereof, nearer the head,

is the form 220, which may engage the head and rotate with it, in which case a coil may be wound into the winding groove formed by the cooperating head and form. The axial movement of the tail shaft is controlled and effected by the operator through a foot pedal 221. The shafts are mounted on a suitably supported bed 222, upon which may also be mounted a motor (not shown), operatively connected to the loose pulley by a belt or chain. Slidably mounted on head shaft 212 and keyed thereto is a clutch 224 whose face may be pressed against pulley 214 by a heavy coiled compression spring 213 disposed on the shaft between the collar 225 of clutch 224 and a stationary bearing 226 in which the head shaft is journaled. When the clutch is in, the head shaft is rotated and by means of ratchet wheels 226a on counter shaft 216 and pawls 227 on head shaft 212, the former shaft is caused to rotate, step by step. The pawls are held down by leaf springs 228 and the ratchets 226a are removable and replaceable by others if desired, to vary the intermittent rotation of the countershaft. As the counter shaft rotates, a lobe 230 of a cam 229 carried by said shaft, passes the end of a horizontal rocker arm 232 thereby rotating the latter clockwise as viewed in Fig. 1 on its vertical axis pivot 233, against the tendency of a torsion spring 234 (see Fig. 6), thereby forcing clutch 224 out of driving engagement with the driving pulley 214. Cam 229 is so designed and so applied that clutch 224 is disengaged from pulley 214 when a coil is completed. In order to prevent rotation of the head beyond a desired angular position after disengagement of the clutch due to the momentum of shaft 212 and head 200, means to prevent such excess rotation are provided. Such means includes a cam 235, mounted on counter-shaft 216 and having a lobe 236 which may actuate the end 237 of a shaft locking crank 238. The latter is journaled in a rubber cushioned bearing bracket 239 and has a hook portion 240 adapted to be disposed in a notch 241 in the periphery of clutch collar 225. At the proper moment, the locking crank will be moved by the cam 236 against the tendency of a tension spring 247a whereby its hook 240 enters notch 241 of the rotating clutch collar 225 and stops rotation of clutch 224 and consequently of the head shaft. When the head has been stopped in proper angular position, the operator depresses foot pedal 221 which is connected to a link 242 by means of a bar 243 and another link 243a, thereby to move downwardly, link 242 whose upper end is connected to a bell crank 244 which is yoked at 245 to a control cone 246, moving the latter to the right (Fig. 2a). Such movement of the control cone causes the bell crank shaped cutting blades 247 to rotate clockwise on their pivots 248 in head 200, and these blades traverse the wires to cut and bend them, in a manner to be described. The depressing of foot pedal 221 also results in downward movement of a link 249 which is also pivotally connected to bar 243 thereby actuating the toggle joint formed by links 250 whereby tail shaft 218 is moved toward the right (Fig. 2a), thus drawing the form away from the head in order to free the completely wound and clipped coil, which may then be removed by the operator. When the operator releases the foot pedal, a coil spring 251 which is attached with one end to the bed 222 and with the other end to bar 243 adjacent link 249 pulls bar 243 upwardly thereby causing the tail shaft 218 to be moved toward the head shaft 212 to clutch the form to the

head and the bell crank 244 to be returned from the position shown in Fig. 8 to that shown in Figs. 2a and 9. As clearly shown in Fig. 2a, the pivot connection between link 243a and bar 243 is closer to link 242 than to link 249. Therefore, upon depressing of foot pedal 221 link 242 will be first moved downwardly until the cone 246 has actuated the cutting blades 247 which then prevent any further downward movement of link 242, and then link 249 will be moved downwardly against the tendency of spring 251 whereby the form is withdrawn from the head. Upon release of the foot pedal by the operator, the spring 251, due to its closer location to link 249 urges the latter upwardly until the form is again in operative engagement with the head and thereupon the spring 251 will rotate bar 243 clockwise (see Fig. 2a) about the now stationary pivot point between bar 243 and link 249 and cause bell crank 244 to be returned into the position shown in Fig. 2a.

When the yoked end of bell crank 244 returns to its original position, Fig. 2a, a spring depressed wedge-end starting cam 251a (Figs. 8, 9 and 10) carried thereby, slides on an anti-friction roller 252a of a stop rod 252 underneath a clevis 253 which is secured to the countershaft 216, thereby rotating the latter sufficiently to move lobes 230 and 236 of cams 229 and 235, respectively, from the clutch control rocker arm 232 and from the shaft locking crank 238, respectively. These parts then release the clutch and permit the heavy coil spring 213 to expand and to clutch the head shaft to the loose pulley once more, for rotation of the shafts and the head. It will be noticed in Fig. 7 that upon rotation of shaft 216 in the direction of arrow 7a as caused by starting cam 251a, cam lobe 236 will move out of engagement with the shaft locking crank 238 before cam lobe 230 moves out of engagement with clutch rocker arm 232. In this manner it is assured that the clutch will not be in driving engagement with the driving pulley 214 before said clutch is free to rotate.

From the foregoing, it will be understood that immediately upon release of foot pedal pressure by the operator, the winding form parts come together and rotate, continuing so to do, without further attention upon the part of the operator, until the coil is completely wound, at which time the winding head will have assumed its rest position, and will have stopped. Then the operator will depress the foot pedal to cut off and free the completed coil, without danger of the head starting to rotate, the shaft being locked until the foot pedal pressure is released once more.

The head 200 in general, is elongated and when in its rest position, is disposed with its long dimension vertical (see Figs. 18 and 21). On one face, it is cut away to provide a seat into which may be disposed and securely held an insert 260 (Figs. 11 and 12). The insert and the head are transversely bored so that they may fit on the end of the head shaft 212, and the head is removably, but securely fixed to the shaft end by screws, pins, etc., as desired. The head may be removed and replaced by another, if desired, and the inserts may be removed and replaced on the head.

70. The insert is provided with projecting portions 261 which engage similar portions 262 on the form 220 to create a winding groove as explained with reference to Figs. 23 to 45 inclusive, in which a wire or wires may be wound. The projecting portions 261 and 262 when in engagement with

each other form a driving connection between the head and the form.

The head 200 is provided with two relatively transverse intersecting slots 265 and 266. The slot 265 which is parallel to the axis of the head shaft, is considerably deeper and wider than the slot 266, and receives the blades 247 which are pivoted to the head by a pin 248. The slot 266 which is perpendicular to the plane of movement of the blades 247, is shallow and very narrow, 10 and receives the wires to be traversed and anchored by the blades. The walls of slot 265 are provided with hardened plates 267 along which move the edges of the blades 247. The blades 247 are pinned together by a pin which is pressfitted into holes 268 of these blades. They are provided with pivot holes 269 for receiving pivot 248, and have ends 270 which may be engaged by the control cone 246, whereby they may be moved. The blade near the operator is nothing more than a 20 cutting blade and accordingly has nothing more than a cutting edge 271. The blade more remote from the operator, and nearer the spools from which wires are fed, has two edges 272 and 273, one above the other, they being separated by a 25 tooth 274. The edge 272 is dull, being only a bending edge, while the one at 273, being for cutting, is very sharp.

In back of the head, near the end of the countershaft 216 is a wire shifter (Figs. 1a, 16, 17 and 21) comprising a bell crank 276 pivotally mounted at 277 to bed 222 and having a freely rotating wheel 278 over which the wires pass on their way from the spools to the winding form. An anti-friction roller carried by bell crank 276 is urged by a spring urged plunger 279 into engagement with a disc cam 280 which is attached to countershaft 216 and actuates said wire shifting wheel 278 in such manner that the latter properly guides the wires into the winding groove. 40

When a coil is to be wound, the leading ends of the wires, as they come from the spools are disposed in the slot 266 of the head 200. The blades 247 at this time, are in the dot-and-dash position of Fig. 13, with slot 266 clear except for 45 blade tooth 274 partly traversing the slot so that the wires rest on tooth 274, however, there is enough clearance between said tooth 274 and the corner 500 (see Fig. 14) to permit anchors to move underneath blade tooth 274. The foot 50 pedal is depressed and the blades move from the dot-and-dash position in Fig. 13 to the full line position thereof, whereby bending edge 272 bends the leading ends into hooks or anchors, these being clamped in a cut away portion of the rear blade (see Fig. 12) between this blade and the rear plate 267. The head starts to rotate, and the ends 270 of the blades are engaged by the inside surface 282 of a stationary cam 283 (Fig. 18) which forces the blades back into the dot-and-dash position of Fig. 13. The bending edge 272 which had been engaging the anchors, now 60 frees them, and the tension of the spools on the wires pulls the anchors all the way down into the slot 266, below blade tooth 274, which is once 65 more partly crossing slot 266, above the anchors. The winding parts rotate, and when the last turn is finished, the wires are shifted in a manner to be described later by wheel 278 into the wire slot 266, there resting on tooth 274 in the slot. 70 The operator now clips a side of the wound coil in a spring clip 284 (Fig. 12) disposing the latter in notches 285 in the edges of the head and form. While so holding the coil, the operator depresses pedal 221, which action causes control 75

cone 246 to push blades 247 into the head. Edge 271 of the forward blade will cut the wires to sever the trailing ends from the wires coming from the spool. Edge 273 will cut the anchor 5 ends off the leading ends of the coil, and edge 272 will bend the leading ends of the wires of the next coil to be wound into anchors, as before. At the same time, form 220 is drawn back and the coil is free to be removed from the machine. Releasing of the pedal starts a new winding operation. Due to the fact that the cutting edge 273 is below the bending edge 272, and due to the fact that the anchors have been drawn down below the trailing ends of the wires, there is no 10 danger that cutting off the anchors of the completed coil will also cut off the anchors of the wires coming from the spools.

In order that the machine may produce the coil of the Cullin application it is obvious that 20 the cam 280 which controls the wire cutting mechanism and the wire shifter must be constructed in the manner now to be described. Referring to Figs. 11, 12 and 21 to 45 inclusive, the start leads 130c, consisting of wires 147 and 148 are anchored in the manner previously explained. Upon starting of the machine, cam 280 actuates the wire shifter in such manner that the start leads 130c of a coil to be wound are deposited in groove 142 of winding form 135 during 25 substantially the first quarter revolution of said winding form. Wire 147 is on top of wire 148. During the next quarter revolution of the winding form wires 147 and 148 are deposited into the continued groove 142a of said winding form. During the next quarter revolution of 30 the winding form the wires leave form groove 142a and are deposited on form surface 137 and in snug engagement with form surface 143. Wire 147 is still on top of wire 148, as shown in Fig. 25. During the next quarter revolution of the winding form, the wires are shifted from surface 143 over to surface 144, such crossing being partly controlled by the tapered form surface 141 and 35 138 and by the wire shifter. At the start of the crossing, the wire 147 is still on top of wire 148. As earlier stated, the wire shifter 278 shifts the wires twice during each revolution of the winding form, except the first time during the first revolution of the winding form, at which time the wire shifter guides the wires properly into 40 the continuing grooves 142 and 142a of the winding form. After such deposition of these wires in form grooves 142 and 142a, the cam disc 280 whose true contour is shown in Fig. 16 actuates 45 the wire shifter regularly twice during each revolution of the winding form. One end of form groove 142a merges into the groove 266 from which the anchored leads 130c extend. After the wires 147 and 148 move out of engagement with form surface 145, wire 147 comes to lie side by side with wire 148. The distance between the centers of the two annular grooves of the wire shifter wheel 278 is approximately the distance 50 A shown in Fig. 30; however, due to the fact that surface 136 of the winding form is tapered, wire 147 will be urged into snug engagement with wire 148. During the next quarter revolution of the winding form, the wires 147, 148 pass along side winding form surface 144 (see Fig. 27). Again the tapered surface 136 of the winding form urges wire 147 into snug engagement with wire 148. During the next quarter revolution 55 the wires are shifted from form surface 146 into engagement with the lower wire 148 of the first deposited coil turn. Again the tapered surface 70 75

140 of the winding form urges wire 148 into snug engagement with wire 147 in spite of the greater distance between the centers of the shifter wheel grooves. During the next quarter revolution the wires remain in engagement with the lower wire 148 of the first deposited coil turn. During the following quarter revolution of the winding form, wires 147 and 148 for a short distance follow the previously deposited wires 147 and 148 until the wire shifter 278 directs the same across these 10 previously deposited wires 147 and 148. From now on until the end of the winding operation, one wire will be deposited on the side of a previously deposited bottom wire and the other wire will be deposited on top of a previously deposited 15 wire. The wire shifter wheel 278 does not interfere with such wire deposition because, as already explained, the distance between the grooves of said wire shifter wheel is A. The figures following Fig. 30 in successive order illustrate the 20 further development of the coil. In maintaining the explained winding order throughout the remaining winding operation it is apparent from Figs. 23 to 45 inclusive, that the wires 147 and 148 are but for two instances located on the 25 bottom and top, respectively, of coil side 130, and that the wires 147 and 148 are but for one instance on the top and bottom, respectively, of coil side 131. During the last quarter revolution of the winding form during a winding operation, 30 the depression 300 of cam disc 280 causes the wire shifter to shift the trailing coil leads 131c into a notch 301 (see Fig. 22) of the winding head 200 which leads to the cutting groove 266. There will be no detailed description of the contour of cam disc 280, since the cooperation between the intermittently rotated cam disc and the wire shifter has been sufficiently explained. After the machine comes to rest, the operator 35 merely takes the wound coil from the winding form in the earlier explained manner. The end leads 130c and 131c which emerge from coil sides 130 and 131 will subsequently be straightened so as to assume the position shown in Fig. 4 and the coil sides 130 and 131 will be wrapped by suitable strips of paper or like material, whereby the individual turns of the coil remain in proper relationship to each other if not otherwise forced out of such relationship by intentionally applied 40 external forces.

Fig. 46 shows clearly the shape of the winding groove. It will be noticed that the corners 501 to 504, inclusive, in which the bottoms of active coil side receiving and coil end receiving groove portions and certain of the two side walls of the 55 winding groove meet, are deep corners of the winding groove. This figure in a most comprehensive manner also illustrates the slanting of the bottom of the winding groove.

Figs. 48 to 55 inclusive illustrate the gradual 60 slanting of the bottom of a coil end receiving groove portion toward the above mentioned corners 501 and 504.

While the form of embodiment of the present invention as herein disclosed, constitutes a preferred form, it is to be understood that other forms might be adopted, all coming within the scope of the claims which follow.

What is claimed is as follows:

1. In a coil winding machine, a winding form 70 including means to bend the start of a supply wire into an anchor hook which secures itself to the head, means to sever the anchor hook from the leading end of a wound coil, and means to prevent the start of the supply wire from being 75

- disposed into cooperative engagement with the anchor severing means and to retain the start of said supply wire in cooperative engagement with the anchor bending means.
5. In a coil winding machine, a winding form including means to sever the trailing end of a wound coil from a supply wire, to bend the severed end of the supply wire into an anchor hook which secures itself to the form, and to sever the anchor hook in the bend thereof from the leading end of the wound coil.
6. In a coil winding machine, a winding form including means to sever the trailing end of a wound coil from a supply wire, means to bend the severed end of the supply wire into an anchor hook which secures itself to the form, means to sever the anchor hook from the leading end of the wound coil, and means between the anchor bending means and the anchor severing means for preventing said severed end of the supply wire from being disposed into cooperative engagement with the anchor severing means.
7. In a coil winding machine, a winding form including relatively movable means to sever the trailing end of a wound coil from a supply wire, relatively movable means to bend the severed end of the supply wire into an anchor hook which secures itself to the head, relative movable means to sever the anchor hook from the leading end of the wound coil, and means between the anchor bending means and the anchor severing means for preventing said severed end of the supply wire from being disposed into cooperative engagement with the anchor severing means, and the anchor bending means relatively moving outside of the path of relative movement of the anchor severing means.
8. In a coil winding machine, a winding form including a plurality of means operable simultaneously to bend the start of a supply wire into an anchor hook which secures itself to the head and to sever the anchor hook from the leading end of a wound coil, and means to prevent the start of the supply wire from being disposed into cooperative engagement with the anchor severing means.
9. In a coil winding machine, a winding form providing a portion having two relatively transverse intersecting slots in one of which the start of a supply wire is deposited; and an element pivotally mounted in the other slot and operable to bend said start of the supply wire into said other slot thereby anchoring the same to the form.
10. In a coil winding machine, a winding form providing a winding groove, a portion having two relatively transverse intersecting slots in one of which the start of a supply wire is deposited, and a groove leading from the wire depositing slot to the winding groove for guiding the starting end of a coil to be wound into said winding groove; and means in the other slot for bending the start of the supply wire into said other slot thereby anchoring said start of the supply wire to the winding form.
11. In a coil winding machine, a winding form providing a winding groove, a portion having two relatively transverse intersecting slots in one of which the trailing end of a wound coil is deposited, and grooves leading from either end of the depositing slot to the winding groove, one of said grooves guiding the anchored starting end of a coil to be wound into the winding groove and the other of said grooves guiding the trailing end of a wound coil from the winding groove into the wire depositing slot; and means in the other slot for severing the trailing end of a wound coil from the supply wire and for bending the severed end of the supply wire into said other slot thereby anchoring said severed end of the supply wire to the winding form.
12. In a coil winding machine, a winding form having a portion provided with two relatively transverse intersecting slots; and an element pivotally mounted in one of said slots, said element having a shearing edge cooperating with a shearing edge in which two sidewalls of the slots meet for severing the trailing end of a wound coil from a supply wire, and a bending edge for bending the severed end of the supply wire which extends across said one slot into the other slot, thereby anchoring the same to the winding form.
13. In a coil winding machine, a rotatable winding form having a portion provided with two relatively transverse intersecting slots; an element pivotally mounted in one of said slots, a side surface of the element adjacent a side wall of said one slot terminating into a shearing edge cooperating with an edge in which two side walls of the slots meet for severing the trailing end of a wound coil from a supply wire, part of the opposite side surface of the element being spaced from the adjacent side wall of said one slot and terminating into a bending edge for bending the severed end of the supply wire against said adjacent side wall of said one slot thereby anchoring the same to the form, another part of the last mentioned side surface of the element closer to the bottom of said one slot terminating into a shearing edge cooperating with an edge in which said adjacent side wall of said one slot and a side wall of the other slot meet for severing the bent anchor end of a wound coil from the leading end thereof, and the bending edge of the element being separated from the anchor end shearing edge thereof by a tooth which in inoperative position of the element extends partially into said other slot, permitting a bent anchor end to slide toward the bottom of said one slot into operative alignment with the anchor end shearing edge of the ele-

ment; and means for guiding the trailing end of a wound coil into said other slot in such manner that said trailing end comes to rest against the tooth of the element before being severed 5 from the supply wire.

14. In a coil winding machine, the combination of a rotatable winding form; a member co-operating with the form and carried thereby for severing the trailing end of a coil from a supply wire, for forming the severed end of the supply wire into a hook, for anchoring the hook in the form and for severing the hook from the leading end of the coil; means for moving the member into operating position; and a stationary cam for moving the member into inoperative position upon a partial revolution of the form. 10

15. In a coil winding machine the combination of a rotatable winding form providing a winding groove; a member cooperating with the form and carried thereby for severing the trailing end of a coil from a supply wire, for securing the severed end of the supply wire to the form, and for releasing the leading end of the coil from the form; a movable wire guide; means actuated in response to rotation of the form for actuating the wire guide so as properly to guide the wire into the winding groove and the trailing end of the coil into operative engagement with the member; and means for actuating the 20 member. 25

16. In a coil winding machine, the combination of a rotatable winding form providing a winding groove; a member cooperating with the form and carried thereby for severing the trailing end of a coil from a supply wire, for securing the severed end of the supply wire to the form, and for releasing the leading end of the coil from the form; a movable wire guide; a rotatable shaft parallel to the axis of rotation of the form; means for intermittently rotating the shaft in response to rotation of the form in one direction; a cam on the shaft for causing the wire guide properly to guide the wire into the winding groove and the trailing end of a coil into operative engagement with the member; and means for actuating the member. 30

17. In a coil winding machine, the combination of a rotatable winding form; a member co-operating with the form and carried thereby for severing the trailing end of a coil from a supply wire, for securing the severed end of the supply wire to the form, and for releasing the leading end of the coil from the form; means actuated in response to rotation of the form for guiding the trailing end of the coil into cooperative position with said member; means for moving said member into operating position; and means responsive to a partial revolution of the form for moving the member into inoperative position. 35

18. In a coil winding machine, the combination of a rotatable winding form; a power driven pulley loosely mounted on the winding form; a slideable clutch on said winding form to clutch the latter to the pulley; yielding means tending to cause clutch engagement; a pivotally mounted clutch disengaging arm; an operable member co-operating with the form and carried thereby for severing the trailing end of a coil from a supply wire, for securing the severed end of the supply wire to the form and for releasing the leading end of the coil from the form; and means actuated in response to rotation of the form for actuating said arm and for guiding the trailing end of the coil into operative engagement with said member. 40

19. In a coil winding machine, the combination

of a rotatable winding form; a power driven pulley loosely mounted on the winding form; a slideable clutch on said winding form to clutch the latter to the pulley; yielding means tending to cause clutch engagement; a pivotally mounted clutch disengaging arm; an operable member co-operating with the form and carried thereby for severing the trailing end of a coil from a supply wire, for securing the severed end of the supply wire to the form and for releasing the leading end of the coil from the form; a wire shifter; means actuated in response to rotation of the form for causing the wire shifter properly to guide the wire to the form, and actuated in response to a certain number of completed revolutions of the form for causing the wire shifter to guide the trailing end of the coil into operative engagement with the member; and means actuated in response to rotation of the form for actuating the arm. 10 15

20. In a coil winding machine, the combination of a rotatable winding form; a power driven pulley loosely mounted on the winding form; a slideable clutch on said winding form to clutch the latter to the pulley; yielding means tending to cause clutch engagement; a pivotally mounted clutch disengaging arm; a member cooperating with the form and pivotally mounted thereon for severing the trailing end of a coil from a supply wire, for securing the severed end of the supply wire to the form and for releasing the leading end of the coil from the form; means for rotating the member into operative position; means actuated in response to rotation of the form for actuating said arm and for guiding the trailing end of the coil into operative engagement with 20 25 30 said member; and means returning the member into inoperative position in response to a partial revolution of the form. 35

21. In a coil winding machine, a rotatable winding form; a loosely mounted pulley on the form; a slideable clutch on the form to clutch the latter to the pulley; yielding means tending to cause clutch engagement; a pivotally mounted clutch disengaging arm; locking means for preventing rotation of the form; means for actuating the 40 45 arm; and means actuated in response to operation of the arm actuating means for actuating the locking means. 50

22. In a coil winding machine, a rotatable winding form providing a winding groove; a loosely mounted pulley on the form; a slideable clutch on the form to clutch the latter to the pulley; yielding means tending to cause clutch engagement; a pivotally mounted clutch disengaging arm; an operable member cooperating with the form and 55 carried thereby for severing the trailing end of a coil from a supply wire, for securing the severed end of the supply wire to the form and for releasing the leading end of the coil from the form; locking means for preventing rotation of the form; and means actuated in response to rotation of the form for actuating said arm, for guiding the trailing end of the coil into operative engagement with said member, and for actuating said locking means. 60 65

23. In a winding machine, a rotatable winding form providing a winding groove; a loosely mounted pulley on the form; a slideable clutch on the form to clutch the latter to the pulley; yielding means tending to cause clutch engagement; a pivotally mounted clutch disengaging arm; an operable member cooperating with the form and carried thereby for severing the trailing end of a coil from a supply wire, for securing the severed end of the supply wire to the form and for re- 70 75

- leasing the leading end of the coil from the form; locking means for preventing rotation of the form; a wire shifter, means actuated in response to rotation of the form for causing the wire shifter properly to guide the wire into the winding groove and the trailing end of the coil into operative engagement with the member; and means actuated in response to a certain number of completed revolutions of the form for actuating the arm and the locking means.
24. In a coil winding machine, a rotatable winding form providing a winding groove; a loosely mounted pulley on the form; a slideable clutch on the form to clutch the latter to the pulley; yielding means tending to cause clutch engagement; a pivotally mounted clutch disengaging arm; a member cooperating with the form and pivotally mounted thereon for severing the trailing end of a coil from a supply wire, for securing the severed end of the supply wire to the form and for releasing the leading end of the coil from the form; locking means for preventing rotation of the form; a wire shifter; means for moving the member into operative position; means actuated in response to rotation of the form for causing the wire shifter properly to guide the wire into the winding groove and the trailing end of the coil into operative engagement with the member; means actuated in response to a certain number of completed revolutions of the form for actuating the arm and the locking means; and means returning the member into inoperative position in response to a partial revolution of the form.
25. In a coil winding machine, the combination of a rotatable winding form providing a winding groove; a member carried by the form and cooperating therewith for severing the trailing end of a coil from a supply wire, for securing the severed end of the supply wire to the form and for releasing the leading end of the coil from the form; a movable wire guide; means responsive to rotation of the form for actuating the wire guide so as properly to guide the wire into the winding groove and to shift the trailing end of the coil into operative engagement with the member; and means including a manually operable element for actuating the member and for causing the wire guide actuating means to return the wire guide into position for guiding the wire into the winding groove.
26. In a coil winding machine the combination of a rotatable winding form comprising a winding groove; a member carried by the form and cooperating therewith for severing the trailing end of a coil from a supply wire, for securing the severed end of the supply wire to the form and for releasing the leading end of the coil from the form; means for driving the form; and means including a manually operable element for actuating the member and for causing operation of the driving means.
27. In a coil winding machine the combination of a rotatable winding form comprising a winding groove; a member carried by the form and cooperating therewith for severing the trailing end of a coil from a supply wire, for securing the severed end of the supply wire to the form and for releasing the leading end of the coil from the form; means for driving the form; means including a manually operable element for actuating the member and for causing operation of the driving means; and means actuated in response to rotation of the form for rendering the driving means ineffective.
28. In a coil winding machine, the combination of a rotatable winding form comprising a winding groove; a member carried by the form and cooperating therewith for severing the trailing end of a coil from a supply wire, for securing the severed end of the supply wire to the form and for releasing the leading end of the coil from the form; a movable wire guide; means actuated in response to rotation of the form for actuating the wire guide so as properly to guide the wire into the winding groove and to shift the trailing end of the coil into operative engagement with the member; means for driving the form; and means including a manually operable element for actuating the member, for causing the wire guide actuating means to return the wire guide into position for guiding the wire into the winding groove and for causing operation of the driving means.
29. In a coil winding machine, the combination of a rotatable winding form; a member carried by the form and cooperating therewith for severing the trailing end of a coil from a supply wire, for securing the severed end of the supply wire to the form and for releasing the leading end of the coil from the form; means for locking the form against rotation during rest periods; and means including a manually operable element for actuating the member and for releasing the locking means from the form.
30. In a coil winding machine, the combination of a rotatable winding form; a member carried by the form and cooperating therewith for severing the trailing end of a coil from a supply wire, for securing the severed end of the supply wire to the form and for releasing the leading end of the coil from the form; means for locking the form against rotation during rest periods; and means including a manually operable element for actuating the member, for releasing the locking means from the form and for causing operation of the driving means.
31. In a coil winding machine, the combination of a rotatable winding form; a member carried by the form and cooperating therewith for severing the trailing end of a coil from a supply wire, for securing the severed end of the supply wire to the form and for releasing the leading end of the coil from the form; means for driving the form; means for locking the form against rotation during rest periods; means including a manually operable element for actuating the member, for releasing the locking means from the form and for causing operation of the driving means; and means responsive to rotation of the form for rendering the driving means ineffective and the locking means effective.
32. In a coil winding machine, the combination of a rotatable winding form providing a winding groove; an operable member carried by the form and cooperating therewith for severing the trailing end of a coil from a supply wire, for securing the severed end of the supply wire to the form and for releasing the leading end of the coil from the form; a movable wire guide; means responsive to rotation of the form for actuating the wire guide so as properly to guide the wire into the winding groove and to shift the trailing end of the coil into operative engagement with the member; means for driving the form; means for locking the form against rotation during rest periods; and means including a manually operable element for causing the wire guide actuating

periods; and means including a manually operable element for actuating the member, for releasing the locking means from the head and for causing relative axial movement between the head and form to engage and disengage the same.

43. In a coil winding machine, the combination of a rotatable head; a form rotatable coaxially of the head and defining together with the engaged head a winding groove; a member carried by the head and cooperating therewith for severing the trailing end of a coil from a supply wire, for securing the severed end of the supply wire to the head and for releasing the leading end of the coil from the head; means for driving the head; means for locking the head against rotation during rest periods; and means including a manually operable element for actuating the member, for causing operation of the driving means, for releasing the locking means from the head and for causing relative axial movement between the head and form to engage and disengage the same.

44. In a coil winding machine, the combination of a rotatable head; a form rotatable coaxially of the head and defining together with the engaged head a winding form; an operable member carried by the head and cooperating with the same for severing the trailing end of a coil from a supply wire, for securing the severed end of the supply wire to the head and for releasing the leading end of the coil from the head; a movable wire guide; means responsive to rotation of the head for actuating the wire guide so as properly to guide the wire into the winding groove and to shift the trailing end of the coil into operative engagement with the member; means for driving the head; and means including a manually operable element for causing the wire guide actuating means to return the wire guide into position for guiding the wire into the winding groove, for causing relative axial movement between the head and form to engage and disengage the same.

45. In a coil winding machine the combination of a rotatable head; a form rotatable coaxially of the head and defining together with the engaged head a winding groove; a member carried by the head and cooperating therewith for severing the trailing end of a coil from a supply wire, for securing the severed end of the supply wire to the head and for releasing the leading end of the coil from the head; a movable wire guide; means responsive to rotation of the head for actuating the wire guide so as properly to guide the wire into the winding groove and to shift the trailing end of the coil into operative engagement with the member; means for locking the head against rotation during rest periods; and means including a manually operable element for causing the wire guide actuating means to return the wire guide into position for guiding the wire into the winding groove, for releasing the locking means from the head and for causing relative axial movement between the head and form to engage and disengage the same.

46. In a coil winding machine the combination of a rotatable head; a form rotatable coaxially of the head and defining together with the engaged head a winding groove; an operable member carried by the head and cooperating therewith for severing the trailing end of a coil from a supply wire, for securing the severed end of the supply wire to the head and for releasing the leading end of the coil from the head; a movable wire guide; means responsive to rotation of the head for actu-

ating the wire guide so as properly to guide the wire into the winding groove and to shift the trailing end of the coil into engagement with the member; means for driving the head; means for locking the head against rotation during rest periods; and means including a manually operable element for causing the wire guide actuating means to return the wire guide into position for guiding the wire into the winding groove, for causing operation of the driving means, for releasing the locking means from the head and for causing relative axial movement between the head and form to engage and disengage the same.

47. In a coil winding machine, the combination of a rotatable head; a form rotatable coaxially of the head and defining together with the engaged head a winding groove; a member carried by the head and cooperating therewith for severing the trailing end of a coil from a supply wire, for securing the severed end of the supply wire to the head and for releasing the leading end of the coil from the head; a movable wire guide; means responsive to rotation of the head for actuating the wire guide so as properly to guide the wire into the winding groove and to shift the trailing end of the coil into operative engagement with the member; means for locking the head against rotation during rest periods; and means including a manually operable element for actuating the member, for causing the wire guide actuating means to return the wire guide into position for guiding the wire into the winding groove, for releasing the locking means from the head and for causing relative axial movement between the head and form to engage and disengage the same.

48. In a coil winding machine, the combination of a rotatable head; a form rotatable coaxially of the head and defining together with the engaged head a winding groove; a member carried by the head and cooperating therewith for severing the trailing end of a coil from a supply wire, for securing the severed end of the supply wire to the head and for releasing the leading end of the coil from the head; a movable wire guide; means responsive to rotation of the head for actuating the wire guide so as properly to guide the wire into the winding groove and to shift the trailing end of the coil into operative engagement with the member; means for locking the head against rotation during rest periods; and means including a manually operable element for actuating the member, for causing the wire guide actuating means to return the wire guide into position for guiding the wire into the winding groove, for causing operation of the driving means and release of the locking means from the head, and for causing relative axial movement between the head and form to engage and disengage the same.

49. In a coil winding machine, a winding form providing a winding groove comprising two opposite first groove portions receiving active coil sides and two opposite second groove portions receiving coil ends, the first groove portions having substantially parallel bottoms and being of uniform width, part of the bottom of a second groove portion slanting toward a corner in which said bottom and the bottom of a first groove portion and a side wall of the winding groove meet, and part of the bottom of the opposite second groove portion slanting toward a corner in which said bottom and the bottom of the other first groove portion and the other side wall of the winding groove meet, and both slanting bottom

parts progressing toward their opposite second groove portion.

50. In a coil winding machine, a winding form providing a winding groove comprising two opposite first groove portions receiving active coil sides and two opposite second groove portions receiving coil ends, the first groove portions having substantially parallel bottoms and being of uniform width, part of the bottom of a second groove portion slanting toward a corner in which said bottom and the bottom of a first groove portion and a side wall of the winding groove meet, and part of the bottom of the same second groove portion slanting toward a corner in which said bottom and the bottom of the other first groove portion and the other sidewall of the winding groove meet, and both slanting bottom parts progressing toward the opposite second groove portion.

20 51. In a coil winding machine, a winding form
providing a winding groove comprising two op-
posite first groove portions receiving active coil
sides and two opposite second groove portions re-
ceiving coil ends, the first groove portions having
25 substantially parallel bottoms and being of uni-
form width, part of the bottoms of the second
groove portions slanting toward corners in which
said bottoms and the bottom of a first groove
portion and a side wall of the winding groove
30 meet, and another part of a second groove por-
tion slanting toward a corner in which said bot-
tom and the bottom of the other first groove por-
tion and the other side wall of the winding groove
meet, and all slanting bottom parts progressing
35 toward their opposite second groove portion.

53   52. In a coil winding machine, a winding form
providing a winding groove comprising two op-
posite first groove portions receiving active coil
sides and two opposite second groove portions re-
40 ceiving coil ends, the first groove portions having
substantially parallel bottoms and being of uni-
form width, part of the bottoms of the second
groove portions slanting toward corners in which
said bottoms and the bottom of a first groove
45 portion and a side wall of the winding groove
meet, and another part of the same bottoms slant-
ing toward corners in which said bottoms and the
bottom of the other first groove portion and the
other side wall of the winding groove meet, and
50 all slanting bottom parts progressing toward their
opposite second groove portion.

53. In a coil winding machine, a winding form providing a winding groove comprising two opposite first groove portions receiving active coil sides and two opposite second groove portions receiving coil ends, the first groove portions having substantially parallel bottoms and being of uniform width, and the second groove portions being of varying width and narrowest at their center 55 portions and widest where they merge into the first groove portions.

54. In a coil winding machine, a winding form providing a winding groove comprising two opposite first groove portions receiving active coil sides and two opposite second groove portions receiving coil ends, the first groove portions being of uniform width and having substantially parallel bottoms, and the second groove portions being of varying width and narrowest at their center portions and widest where they merge into the first groove portion, part of the bottom of a second groove portion slanting toward a corner in which said bottom and the bottom of a first groove portion and a side wall of the winding groove meet, part of the bottom of the opposite

second groove portion slanting toward a corner in which said bottom and the bottom of the other first groove portion and the other side wall of the winding groove meet, and both slanting bottom parts progressing toward their opposite second groove portion.

55. In a coil winding machine, a winding form providing a winding groove comprising two opposite first groove portions receiving active coil sides and two opposite second groove portions receiving coil ends, the first groove portions being of uniform width and having substantially parallel bottoms, and the second groove portions being of varying width and narrowest at their center portions and widest where they merge into the first groove portions, part of the bottom of a second groove portion slanting toward a corner in which said bottom and the bottom of a first groove portion and a side wall of the winding groove meet, and part of the bottom of the same second groove portion slanting toward a corner in which said bottom and the bottom of the other first groove portion and the other sidewall of the winding groove meet, and both slanting bottom parts progressing toward the opposite second groove portion.

56. In a coil winding machine, a winding form providing a winding groove comprising two opposite first groove portions receiving active coil sides and two opposite second groove portions receiving coil ends; the first groove portions being of uniform width and having substantially parallel bottoms, and the second groove portions being of varying width and narrowest at their center portions and widest where they merge into the first groove portion, part of the bottoms of the second groove portions slanting toward corners in which said bottoms and the bottom of a first groove portion and a side wall of the winding form meet, and another part of the bottom of a second groove portion slanting toward a corner in which said bottom and the bottom of the other first groove portion and the other side wall of the winding form meet, and all slanting bottom parts progressing toward their opposite second groove portion. 30 35 40 45

57. In a coil winding machine, a winding form providing a winding groove comprising two opposite first groove portions receiving active coil sides and two opposite second groove portions receiving coil ends, the first groove portions being of uniform width and having substantially parallel bottoms, and the second groove portions being of varying width and narrowest at their center portions and widest where they merge into the first groove portion, part of the bottoms of the second groove portions slanting toward corners in which said bottoms and the bottom of a first groove portion and a side wall of the winding form meet, and another part of the same bottoms slanting toward corners in which said bottom and the bottom of the other first groove portion and the other side wall of the winding groove meet, and all slanting bottom parts progressing toward their opposite second groove portion.

58. In a coil winding machine, a winding form providing a winding groove comprising two opposite first groove portions receiving active coil sides and two opposite second groove portions receiving coil ends, the first groove portions being of uniform width and the bottom of a first groove portion being tapered with respect to the plane in which the winding groove lies, and part of the bottom of a second groove portion slanting to- 75

ward a corner in which said bottom and the bottom of a first groove portion and a side wall of the winding groove meet.

59. In a coil winding machine, a winding form
5 providing a winding groove comprising two op-
posite first groove portions receiving active coil
sides and two opposite second groove portions
receiving coil ends, the first groove portions be-
ing of uniform width and the bottom of a first
10 groove portion being tapered with respect to the
plane in which the winding groove lies, part of
the bottoms of the second groove portions slant-
ing toward corners in which said bottoms and
the bottom of a first groove portion and a side
15 wall of the winding groove meet, and both slant-
ing bottom parts progressing toward their oppo-
site second groove portion.

60. In a coil winding machine, a winding form providing a winding groove comprising two opposite first groove portions receiving active coil sides and two opposite second groove portions receiving coil ends, the first groove portions being of uniform width and the bottom of a first groove portion being tapered with respect to the plane 20 in which the winding groove lies, part of the bottoms of the second groove portions slanting toward corners in which said bottoms and the bottom of a first groove portion and a side wall of the winding groove meet, and another part of the 25 bottom of a second groove portion slanting toward a corner in which said bottom and the bottom of the other first groove portion and the other side wall of the winding groove meet, and all slanting bottom parts progressing toward 30 the opposite second groove portion.

35

40 61. In a coil winding machine, a winding form
providing a winding groove comprising two op-
posite first groove portions receiving active coil
sides and two opposite second groove portions
receiving coil ends, the first groove portions be-
ing of uniform width and the bottom of a first
groove portion being tapered with respect to the
plane in which the winding groove lies, part of
the bottoms of the second groove portions slant-
ing toward corners in which said bottoms and
the bottom of a first groove portion and a side
wall of the winding groove meet, and another
part of the same bottoms slanting toward corners
in which said bottoms and the bottom of the
other first groove portion and the other side wall
of the winding groove meet, and all slanting bot-
tom parts progressing toward their opposite sec-
ond groove portion.

55 62. In a coil winding machine, a winding form providing a winding groove, those groove portions which receive active coil sides being of uniform width and having substantially parallel bottoms which are tapered with respect to the plane in which the winding groove lies.

60 63. In a coil winding machine, a winding form
providing a winding groove comprising two oppo-
site first groove portions receiving active coil
sides and two opposite second groove portions
receiving coil ends, the first groove portions be-
ing of uniform width and having substantially
parallel bottoms which are tapered with respect
to the plane in which the winding groove lies,
and part of the bottom of a second groove por-
tion slanting toward a corner in which said bot-
tom and the bottom of a first groove portion and
a side wall of the winding groove meet.

64. In a coil winding machine, a winding form providing a winding groove comprising two opposite first groove portions receiving active coil sides and two opposite second groove portions receiv-

and two opposite second groove portions receive

ing coil ends, the first groove portions being of uniform width and having substantially parallel bottoms which are tapered with respect to the plane in which the winding groove lies, part of the bottom of a second groove portion slanting toward a corner in which said bottom and the bottom of a first groove portion and a side wall of the winding groove meet, and part of the bottom of the opposite second groove portion slanting toward a corner in which said bottom and the bottom of the other first groove portion and the other side wall of the winding groove meet, and both slanting bottom parts progressing toward their opposite second groove portion.

65. In a coil winding machine, a winding form 15
providing a winding groove comprising two opposite first groove portions receiving active coil sides and two opposite second groove portions receiving coil ends, the first groove portions being of uniform width and having substantially parallel bottoms which are tapered with respect to the plane in which the winding groove lies, part of the bottom of a second groove portion slanting toward a corner in which said bottom and the bottom of a first groove portion and a side wall of the winding groove meet, and part of the same bottom slanting toward a corner in which said bottom and the bottom of the other first groove portion and the other side wall of the winding groove meet, and both slanting bottom parts progressing toward the opposite second groove portion. 20 25 30

66. In a coil winding machine, a winding form providing a winding groove comprising two opposite first groove portions receiving active coil sides and two opposite second groove portions receiving coil ends, the first groove portions being of uniform width and having substantially parallel bottoms which are tapered with respect to the plane in which the winding groove lies, part of the bottoms of the second groove portions slanting toward corners in which said bottoms and the bottom of a first groove portion and a side wall of the winding groove meet, and another part of the bottom of a second groove portion slanting toward a corner in which said bottom and the bottom of the other first groove portion and the other side wall of the winding groove meet, and all slanting bottom parts progressing toward their opposite second groove portion. 35 40 45 50

67. In a coil winding machine, a winding form
providing a winding groove comprising two opposite
first groove portions receiving active coil
sides and two opposite second groove portions
receiving coil ends, the first groove portions being
of uniform width and having substantially
parallel bottoms which are tapered with respect
to the plane in which the winding groove lies,
part of the bottoms of the second groove portions
slanting toward corners in which said bottoms
and the bottom of a first groove portion and
a side wall of the winding groove meet, and another
part of the same bottoms slanting toward
corners in which said bottoms and the bottom of
the other first groove portion and the other side
wall of the winding groove meet, and all slanting
bottom parts progressing toward their opposite
second groove portion. 55 60 65

68. In a coil winding machine, a winding form providing a winding groove comprising two opposite first groove portions receiving active coil sides and two opposite groove portions receiving coil ends, the first groove portions being of uniform width and the bottom of a first groove portion being tapered with respect to the plane in 75 70

other part of the bottom of a second groove portion slanting toward a corner in which said bottom and the bottom of the other first groove portion and the other side wall of the winding groove meet, and all slanting bottom parts progressing toward their opposite second groove portion.

77. In a coil winding machine, a winding form providing a winding groove comprising two opposite first groove portions receiving active coil sides and two opposite second groove portions receiving coil ends, the first groove portions being of uniform width and having substantially parallel bottoms which are tapered with respect to the plane in which the winding groove lies, the second groove portions being of varying width and narrowest at their center portions and widest where they merge into the first groove portions, part of the bottoms of the second groove portions slanting toward corners in which said bottoms and the bottom of a first groove portion and a side wall of the winding groove meet, and another part of the same bottoms slanting towards corners in which said bottoms and the bottom of the other first groove portion and the other side wall of the winding groove meet, and all slanting bottom parts progressing toward their opposite second groove portion.

78. In a coil winding machine, a rotatable winding form providing a winding groove comprising two opposite first groove portions receiving active coil sides and two opposite second groove portions receiving coil ends, the first groove portions being of uniform width and having substantially parallel bottoms which are tapered with respect to the axis of rotation of the winding form; means provided by the winding form for anchoring the start of the wire thereto, said winding form being also provided with a wire guiding groove starting at the anchoring means and gradually approaching the adjacent high portion of a tapered groove bottom and finally merging into the consecutive second groove portion; means for guiding the wire into the winding groove; and means for shifting the wire guiding means parallel to the axis of rotation of the winding form upon presentation of the second groove portions to the guided wire in such manner that the wire is shifted from the deep portion of one tapered groove bottom toward the deep portion of the other tapered groove bottom whereby the active coil sides are developed from opposite directions, said shifting means being inoperative only at the first presentation of said consecutive second groove portion to the guided wire whereby the start and end leads of a wound coil which emerge from the active coil sides in the same direction are located in opposite end planes of the coil.

79. In a coil winding machine, a rotatable winding form providing a winding groove comprising two opposite first groove portions receiving active coil sides and two opposite second groove portions receiving coil ends, the first groove portions being of uniform width and having substantially parallel bottoms which are tapered with respect to the axis of rotation of the winding form; means provided by the winding form for anchoring the start of the wire thereto, said winding form being also provided with an approximately straight wire guiding groove starting at the anchoring means and gradually approaching the adjacent high portion of a tapered groove bottom and finally merging into the consecutive second groove portion; means for guiding the wire into the winding groove; and means for

shifting the wire guiding means parallel to the axis of rotation of the winding form upon presentation of the second groove portions to the guided wire in such manner that the wire is shifted from the deep portion of one tapered groove bottom toward the deep portion of the other tapered groove bottom whereby the active coil sides are developed from opposite directions, said shifting means being inoperative only at the first presentation of said consecutive second groove portion to the guided wire whereby the start and end leads of a wound coil which emerge from the active coil sides in the same direction are located in opposite end planes of the coil.

80. In a coil winding machine, a rotatable winding form providing a winding groove comprising two opposite first groove portions receiving active coil sides and two opposite second groove portions receiving coil ends, the first groove portions being of uniform width and having substantially parallel bottoms which are tapered with respect to the axis of rotation of the winding form, part of the bottoms of the second groove portions slanting toward corners in which said bottoms and the deep portion of the bottoms of a first groove portion and a side wall of the winding groove meet, and another part of the same bottoms slanting toward corners in which said bottoms and the deep portion of the bottom of the other first groove portion and the other side wall of the winding groove meet, and all slanting bottom parts progressing toward their opposite second groove portions; means provided by the winding form for anchoring the start of the wire thereto, said winding form being also provided with a wire guiding groove starting at the anchoring means and gradually approaching first the adjacent high portion of a tapered groove bottom and then the greater part of the consecutive second groove portion and finally merging into said second groove portion; means for guiding the wire into the winding groove; and means for shifting the wire guiding means parallel to the axis of rotation of the winding form upon presentation of the second groove portions to the guided wire in such manner that the wire is shifted from the deep portion of one tapered groove bottom toward the deep portion of the other tapered groove bottom whereby the active coil sides are developed from opposite directions, said shifting means being inoperative only at the first presentation of said consecutive second groove portion to the guided wire whereby the start and end leads of a wound coil which emerge from the active coil sides in the same direction are located in opposite end planes of the coil.

81. In a coil winding machine, a rotatable winding form providing a winding groove, those groove parts which receive active coil sides having approximately parallel bottoms and being of uniform width, and those groove parts which receive coil ends being of varying width and narrowest at their center portions and widest where they merge into the first mentioned groove parts; means for guiding the wire into the winding groove; and means for shifting the wire guiding means parallel to the axis of rotation of the winding form only when the wire is to be deposited in the second mentioned groove parts.

82. In a coil winding machine, a rotatable winding form providing a winding groove comprising two opposite first groove portions re-

ceiving active coil sides and two opposite second groove portions receiving coil ends, the first groove portions being of uniform width and having approximately parallel bottoms which are tapered with respect to the axis of rotation of the winding form, and the second groove portions being of variable width and narrowest at their center portions and widest where they merge into the first mentioned groove parts; means for guiding the wire into the winding groove; and means for shifting the wire guiding means parallel to the axis of rotation of the winding form only when the wire is to be deposited in the second groove portions and in such manner that the wire guide shifts the wire from the deep portion of one tapered groove bottom toward the deep portion of the other tapered groove bottom whereby the active coil sides are developed from opposite directions.

83. In a coil winding machine, a rotatable winding form providing a winding groove comprising two opposite first groove portions receiving active coil sides and two opposite second groove portions receiving coil ends, the first groove portions being of uniform width and having approximately parallel bottoms, and the second groove portions being of variable width and narrowest at their center portions and widest where they merge into the first groove portions; means for guiding the wire into the winding groove; and means for shifting the wire guiding means parallel to the axis of rotation of the winding form upon presentation of the second groove portions to the guided wire in such manner that the active coil sides are developed from

opposite directions, said means being inoperative at the presentation of only the first one of the second groove portions to the guided wire, whereby the start and end leads of a wound coil which emerge from the active coil sides in the same direction are located in opposite end planes of the coil. 5

84. In a coil winding machine, a rotatable winding form providing a winding groove comprising two opposite first groove portions receiving active coil sides and two opposite second groove portions receiving coil ends, the first groove portions being of uniform width and having approximately parallel bottoms which are tapered with respect to the axis of rotation of the winding form, and the second groove portions being of variable width and narrowest at their center portions and widest where they merge into the first groove portions; means for guiding the wire into the winding groove; and means for shifting the wire guiding means parallel to the axis of rotation of the winding form upon presentation of the second groove portions to the guided wire in such manner that the wire is shifted from the deep portion of one tapered groove bottom toward the deep portion of the other tapered groove bottom whereby the active coil sides are developed from opposite directions, said means being inoperative at the presentation of only the first one of the second groove portions to the guided wire, whereby the start and end leads of a wound coil which emerge from the active coil sides in the same direction are located in opposite end planes of the coil. 10 15 20 25 30
